CLAIM

The ornamental design for a faucet as shown and described.

DESCRIPTION

FIG. 1 is a perspective view of a first embodiment of a faucet showing my new design;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof;

FIG. 7 is a bottom plan view thereof;

FIG. 8 is perspective view of a second embodiment of the faucet showing my new design;

FIG. 9 is a front elevational view of the embodiment shown in FIG. 8;

FIG. 10 is a rear elevational view of the embodiment shown in FIG. 8;

FIG. 11 is a side elevational view of the embodiment shown in FIG. 8;

FIG. 12 is a side elevational view of the embodiment shown in FIG. 8;

FIG. 13 is a top plan view of the embodiment shown in FIG. 8; and,

FIG. 14 is a bottom plan view of the embodiment shown in FIG. 8.

The broken lines shown in the drawings denote boundaries of the claim and form no part thereof.

1 Claim, 14 Drawing Sheets
